FILE CABINET

Earle C. Bullock, Grand Rapids, and Adrian R. Olree, Caledonia, Mich., assignors to Steelcase, Inc., Grand Rapids, Mich., a corporation of Michigan

Filed Mar. 7, 1962, Ser. No. 69,131

Term of patent 14 years

(Cl. D33—19)

FIG. 1 is a front perspective view of a file cabinet showing our new design;

FIG. 2 is a side view of the file cabinet shown in FIG. 1;

FIG. 3 is a front elevational view of the file cabinet shown in FIG. 1;

FIG. 4 is an enlarged fragmentary perspective view of the drawer opening means and the identification bracket adjacent thereto; and

FIG. 5 is a fragmentary vertical, sectional view taken on plane V—V of the cabinet as illustrated in FIG. 4.

The dotted lines showing numerals in FIG. 4 are for illustrative purposes only.

The opposite side of the cabinet is substantially the same in appearance as the side that is shown. The top and back of the cabinet are plain.

We claim:

The ornamental design for a file cabinet, substantially as shown and described.
